UNITED STATES PATENT OFFICE.

HENRY MELVIN BASCOM, OF BROOKLYN, NEW YORK, ASSIGNOR TO AMERICAN TELEPHONE AND TELEGRAPH COMPANY, A CORPORATION OF NEW YORK.

DESIGN FOR A TELEPHONE DESK STAND.

Application filed August 14, 1928. Serial No. 27,808. Term of patent 14 years.

To all whom it may concern:

Be it known that I, HENRY MELVIN BASCOM, a citizen of the United States, residing at Brooklyn, in the county of Kings, State of New York, have invented a new, original, and ornamental Design for Telephone Desk Stand, of which the following is a specification, reference being had to the accompanying drawing, forming a part thereof.

The figure is a perspective view of a telephone desk stand, showing my new design.

I claim:

The ornamental design for a telephone desk stand, as shown.

In witness whereof, I hereunto subscribe my name.

HENRY M. BASCOM.
